UNITED STATES PATENT OFFICE.

FELIX KOCH, OF BELLEVUE, PENNSYLVANIA, ASSIGNOR TO PRESSED STEEL CAR COMPANY, OF PITTSBURG, PENNSYLVANIA, A CORPORATION OF NEW JERSEY.

PASSENGER-CAR.

No. 922,782.

Specification of Letters Patent.

Patented May 25, 1909.

Application filed May 19, 1908. Serial No. 433,664.

To all whom it may concern:

Be it known that I, FELIX KOCH, of Bellevue, Allegheny county, Pennsylvania, have invented certain new and useful Improvements in Passenger-Cars, of which the following is a full, clear, and exact description, reference being had to the accompanying drawings, in which like characters refer to like parts, and in which—

10 Figure 1 is a plan view of nearly one-half of the underframe of a car embodying the elements of said invention; Fig. 2 is a longitudinal section of the same on the line 2—2 of Fig. 1; Fig. 3 is a half transverse section of the same on the line 3—3, Fig. 1; Fig. 4 is a like view on the line 4—4, Fig. 1; Fig. 5 is a like view on the line 5—5, Fig. 1; Fig. 6 is a vertical transverse section through the side of the car superstructure; Fig. 7 is an enlarged detail inside face view of the window sill portion of the structure shown in Fig. 6, and Fig. 8 is a sectional view of the same on line 8—8, Figs. 6 and 7; Fig. 9 is an enlarged vertical sectional view of same on line 9—9, 25 Fig. 7; and Fig. 10 is an enlarged horizontal section of the side structure on line 10—10, Fig. 6.

An object of the present invention is to provide improvements in car underframes and superstructure, especially adaptable to that type of car which is provided with a central inclosed portion with steps at each end thereof and an open portion at each end of the car beyond the car steps.

30 More specifically stated, an object of the present invention is to provide a car underframing in which the side sill construction may be made shallow, proportionately to its width, to give sufficient clearance for the trucks and to permit of the location of car side steps between the car bolsters and substantially within the outside line of the side sill; to provide an improved shock-resisting end construction of the underframe; and to 40 provide an improved superstructure and interior furnishings in which the parts are greatly reduced in number while preserving a neat appearance of the car.

The underframe.—Referring now in detail 50 to the drawings, 1 (Fig. 1) represents the center sills, 2 the end sills of channel-form bent to suitable shape and secured to center sills 1 through means of horizontal gusset plates 3 riveted to the flanges of the end and center sills 4 (Fig. 2) is a coupler of ball or other

usual shape, 5 are modified V-shaped coupling and center sill braces, at each end of the car, the legs of which are riveted to the webs of the center sills. Each brace 5 is provided with a horizontal strengthening flange 60 throughout its length. 6 are the side sills and 7 are cross-bearers connecting, through angle gussets 11, the center sills 1 and side sills 6 (Fig. 5). The car bolsters consist each of a pair of cross-bearers 7 (Figs. 1 and 4) on 65 each side of the center sills; a top member 8 extending from one side of the car to the other across and above the center sills and bent downwardly at the side sills and outwardly beneath said side sills; a bottom 70 member 9 extending from side sill to side sill beneath the center sills of the car and secured at its ends to member 8; a filler casting 10 located between the bottom member 9 and the center sills 1; and a pair of struts 7' 75 between center sills 1 and out of alignment with cross-bearers 7: these parts are suitably connected together. 12 (Fig. 3) is a truss member of channel-shape and downwardly extending flanges extending from side sill to 80 side sill beneath the center sills and secured thereto by angles 13. Truss 12 is secured to side sills 6 by triangular flanged gussets 14 so shaped and mounted on the side sills that their upper edges are inclined downwardly 85 toward the center sills to accommodate the direction of the ends of truss 12. There are preferably two trusses 12 in the car underframe, one on each side of the transverse center of the car. The side sills 6 (Figs. 1, 3, 4 90 and 5) are built up of a plurality of members and for portions of their lengths are substantially box-shape in cross-section. These side sills comprise Z-sections 6^a along their inner sides extending substantially the entire length of the car, or from end sill to end sill; outer angular plates 6^b two or more in number depending upon the number and location of stairways on the side of the car; and brackets 6^c, formed preferably of pressed metal, connecting Z-sections 6^a and outer plates 6^b. In order that the car stairway project as little as possible beyond the side of the car, the width of the side sill is decreased to substantially the thickness of the Z-section 6^a and the lower flange of Z-section 6^a is cut away at the point of location of the stairway. As this materially weakens the strength of the side sill, an angular stiffener plate 6^d is riveted to the inner face of the Z- 95 100 105 110

section 6^a for a distance extending beyond the transverse plane of the ends of the outside angular plates 6^b. These plates 6^a are similar in shape to the outside angular plates 6^b and 5 make the strength of the side sills 6 substantially the same throughout their lengths. The outside angular plates 6^b are further supported by angles 6^c riveted to the outer ends of the upper bolster members 8. On either 10 side of the point of location of the stairway, a pair of brackets 6^d are located one at each end of the cut so that the stairway-hangers and the stairway may be fitted snugly into the pocket or recess thus formed for them. 15 By forming the side sills 6 box-like in structure a strong proportionately shallow side sill is produced and giving sufficient clearance for the trucks, greater interior width to the car and materially lowering the car body. 20 *The superstructure.*—15 (Fig. 6) are side posts extending from side sills 6 upwardly to eave plates 16. Side posts 15 are T-shaped in cross-section being secured at their lower ends to side sills 6 through means 25 of angular gusset plates 17 having one flange riveted to the two members of side sills 6 and the vertical leg riveted to side posts 15. The belt rail consists of a series of pressed metal sections or plates 18 and intervening 30 posts, there being one section between each pair of posts, in line with each other. These sections or plates 18 are provided with securing flanges on each end and a web which is obtuse angular in cross-section. Sections 35 or plates 18 are riveted in place with flanges projecting inwardly and the apices of their webs projecting outwardly. 20 is the side sheeting riveted at its base to the outer member 6^b of the side sill 6, having suitably secured thereto the customary guard rail 21 and secured along its upper edge to the belt rail 18. 22 is the sill plate (Figs. 9 and 10) shaped in cross-section similarly to a bulb angle, the head portion being located inside 40 and projecting over the inner edge of the belt rail 18, the outer angle portion overlapping the upper edge of the side sheeting 20 and forming a finished edge or beading therefor. 23 are wooden strips below and 45 above sill plates 22, on opposite sides of posts 15 each forming, with the opposing flange of post 15, sash guides or jambs. Strips 23 are secured to vertical wooden blocks 24 secured on opposite faces of posts 50 15. 25 is the lower movable sash of the car window, there being one between each pair of posts 15. 26 are lintel strips (Fig. 6) extending between posts 15 in the plane of the upper edges of sashes 25 when closed. 60 27 is the upper immovable sash of the car window, the lintel of which is comprised in eave plates 16 and consists in the lower vertical flange thereof. At a suitable distance up the posts 15 are located gussets 28 to 65 which are riveted seat cross-bearers 29 riveted

eted at their outer ends to gussets 30 supported by seat posts 31 in turn supported by gussets 32 riveted to the metal flooring of the car. There is a suitable number of seat cross-bearers 29 and posts 31. Secured 70 to the outer edges of posts 31 are angles 33 designed to space posts 31 and stiffen the seat structure. Extending along the inner ends of seat cross-bearers 29 is an angle 34 riveted to cross-bearers 29 and in which is 75 secured a cleat 35 between which and the angles 33, a seat 36 fits, a cleat 37 secured to the underside of seat 36 forming a front guide for the seat. 38 is a wearing or finishing strip secured to the forward edge of the 80 seat 36, and 39 is a wooden shoe secured to the underside of seat 36 along its forward edge and adapted to rest against angle 33 to give added support to the forward edge of the seat. 40 is the seat-back. 40^a is a 85 combined seat-back head strip and sash pocket cover hinge strip extending along the upper edge of the seat-back 40 and having hinged thereon the sash pocket covers 41. The superstructure thus far described is comprised in the closed central portion of the car. The open portions of the car located at each end are provided with channel side posts 42 (Fig. 1). The end corner posts 43 are in cross-section of modified semi-circular form being extended on their forward sides in the direction of the dash-board to form suitable securing flange for the dash-board sheeting. The end posts 44 are T-shaped in cross-section and are 90 preferably two in number located near the vertical plane of the center sills. Similar to the end corner posts 43 in shape are end posts 45 of the inclosed portion of the car which are bent inwardly toward the center 95 of the car to form a base for both the side and end sheeting of the inclosed portion of the car:

Having thus described my invention, the following is what I claim as new therein and desire to secure by Letters Patent:

1. In a car, the combination with a channel end sill with rearwardly extending flanges and channel center sills, of horizontal gusset plates connecting the flanges of said end and center sills.

2. In a car, the combination with a bowed channel end sill and channel center sills, of gussets connecting the flanges of said end and center sills.

3. In a car, a side sill comprising a continuous inside member and a plurality of outside members separated from each other in the direction of their lengths and secured to said inside member, with reinforcing means for said inside member opposite the space between said outside members.

4. In a car, a built-up side sill comprising a continuous longitudinal inside member and a plurality of longitudinal outside mem-

- bers connected thereto and separated from each other in the direction of their lengths.
5. In a car, a built-up side sill comprising a continuous longitudinal inside member, 5 transverse brackets extending outwardly therefrom and a plurality of longitudinal members carried by said brackets.
6. In a car, a built-up side sill comprising a **Z**-section longitudinal inside member, 10 metal brackets extending transversely out therefrom and an inverted angle longitudinal member carried by said brackets.
7. In a car, a built-up side sill comprising a **Z**-section longitudinal inside member, 15 metal brackets extending transversely out therefrom and a plurality of inverted angle longitudinal members carried by said brackets.
8. In a car, a built-up side sill comprising a longitudinal **Z**-section inside member with 20 sections of one flange removed to form step recesses, a plurality of brackets carried by said **Z**-section member between said recesses and longitudinal outside members secured to said brackets.
9. A car underframe truss comprising a continuous channel member and triangular gussets connecting the ends of said channel member to the car side sills.
- 20 10. A truss for car underframes comprising a continuous channel member, a triangular gusset for connecting the end of said member to the side sill and suitable connection between the said member and the car center sill.
- 35 11. A truss for car underframes comprising a continuous channel member with its flanges depending and extending between the car center sill with upwardly projecting ends and a triangular gusset having an inclined upper surface for connecting said member to the side sill.
- 40 12. In a car, a superstructure comprising **T**-section posts, an angle belt rail carried thereby, side sheeting secured to said posts and said belt rail and a modified bulb angle-section strip embracing the said belt rail and the upper edge of said sheeting.
- 45 13. In a car, a vertical post, an obtuse angle belt rail secured to said post.
- 50 14. In a car, a vertical post, an obtuse angle belt rail secured to said post and a bulb-angle-section sill plate embracing said belt rail.
15. In a car, a vertical post, an obtuse angle belt rail secured to said post, sheeting secured to said belt rail and a bulb angle-section sill plate embracing said belt rail and the edge of said sheeting.
16. In a car, a plurality of posts and a belt rail comprising a series of obtuse angular sections mounted between said posts.
17. In a car, a plurality of posts, a belt rail made up of a series of sections secured between said posts, side sheeting secured to 65 said rail and a bulb angle-section sill plate embracing said rail and side sheeting.
18. In a car, a belt rail built up of a series of pressed metal sections obtuse angular in cross-section.
19. In a car, a belt rail built up of a series of pressed metal sections obtuse angular in cross-section and having securing flanges.
20. In a car, a belt rail built up of a series of pressed metal sections each having an arched web obtuse angular in cross-section.
21. In a car, a belt rail having deep portions at the car posts and shallow portions between the car posts.
22. In a car, a belt rail having arched portions, angular in cross-section between the car posts.
23. In a car, the combination with **T**-section posts, of a belt rail made up of metal sections having flanges secured to the webs in the plane of the flanges of said posts.
24. In a car, a closure for window sash pockets comprising a bulb angle-section sill plate and a hinged cover recessed to fit the bead on said sill plate.
25. In a car, an eave plate having a vertical lower portion, a horizontal intermediate portion and an inclined upper portion.
26. In a car, an eave plate having a vertical portion secured to the posts, a horizontal intermediate portion and an inclined upper portion secured to the carline.
27. In a car, a built-up side sill comprising a **Z**-section longitudinal inside member and an angle longitudinal outside member spaced from and connected thereto.

The foregoing specification signed at McKees Rocks, Allegheny county, Pennsylvania, this twenty-eighth day of April, 1908.

FELIX KOCH.
